UNITED STATES PATENT OFFICE.

THOMAS WILKINSON AND JOHN GLENDINNING, OF KANSAS CITY, MISSOURI.

SLACK-BURNING FURNACE.

SPECIFICATION forming part of Letters Patent No. 397,951, dated February 19, 1889.

Application filed July 30, 1888. Serial No. 281,368. (No model.)

To all whom it may concern:

Be it known that we, THOMAS WILKINSON and JOHN GLENDINNING, citizens of the United States, residing at Kansas City, in the county of Jackson and State of Missouri, have invented certain new and useful Improvements in Slack-Burning Furnaces; and we do hereby declare the following to be a full, clear, and exact description of the invention, such as will enable others skilled in the art to which it appertains to make and use the same.

Our invention relates to an improvement in slack-burning furnaces.

The object is to provide a furnace of the above character which will effectually consume the slack, and which will at the same time consume the smoke and be self-cleaning.

With these ends in view our invention consists in certain features of construction and combinations of parts, as will be hereinafter described, and pointed out in the claims.

In the accompanying drawings, Figure 1 is a top plan view of the grate. Fig. 2 is a longitudinal vertical section through the grate, the feed, and a portion of the boiler. Fig. 3 is a front view of the furnace-wall and grate-bed and ash-pit, the grate itself being removed; and Fig. 4 is a partial transverse section through grate, showing the grate-bar in cross-section.

A A represent the side walls of the furnace, and B represents an arch over the top of the fire-chamber in front of the boiler. C. Through the arch B is a narrow opening, b, the width of which is preferably coextensive with the width of the arch itself, the said opening extending from the front of the arch toward the boiler and then downwardly, opening into the fire-chamber such a distance from the feed as to furnish air to the fire at that point where the smoke is most dense and the heat sufficient to effectually consume the smoke when aided by the influx of the air. It will be observed that the air is admitted in a thin sheet extending entirely across the top of the fire-chamber, whereby oxygen is furnished to the entire volume of smoke and gas as it flows beneath the boiler.

On the floor a of the furnace and near the side walls, A, are located tracks a', on which the grate is mounted, as will hereinafter appear. Centrally of the floor and extending

lengthwise of the furnace is an ash-pit, a². At the back end of the grate a solid wall of masonry, D, slants upwardly and rearwardly from the furnace-floor, and, as it extends rearwardly below the boiler, serves to support the rear end of the boiler and form a channel for the products of combustion between its upper surface and the boiler.

The grate is mounted upon four cast-iron wheels, E, from the axles e of which standards e' extend upwardly and are firmly united by suitable girders. (Not shown.) In the upper portions of the said standards e' drums F are journaled, one between the two front standards and the other between the two rear standards. On the drums F the grate G is mounted. The said grate forms, as a whole, an endless apron or carrier, which is calculated to travel continuously to carry the slack from the front to the rear along its upper surface as the said slack is gradually fed thereto.

The grate G is composed of a plurality of short bars g, constructed and combined as follows: Each bar g is constructed thicker at its upper edge than at its lower edge, as is usual. The ends of each bar are cut under in curved form, as shown at g', in order to admit of the bars being turned with respect to one another to form the contour of the drums F. Each bar is provided near its ends with perforations extending transversely through the bar, through which rods or bolts H loosely extend to bind the different bars together. The bars are assembled as follows: Beginning with a bar at the outside, the next bar toward the center has its perforation in its forward end placed so as to register with the perforation at the rear end of the outside bar; then comes the next bar toward the center in position directly opposite the outside bar; then comes the next bar toward the center in position directly opposite the second bar mentioned, and so on, the bars when united forming transverse series of parallel bars, each series alternating with the bars of the next series to the front or rear of it. Furthermore, the bars are so spaced apart, either by bosses g³, formed on their sides around the perforations, or by spacing-washers g⁴, inserted between each two, or by both, as to turn freely on their connecting-rods, and also admit the

necessary amount of air to flow up between them to produce effective combustion. The drums F are polygonal in cross-sections, and their flat sides f are of such widths as to exactly correspond to the under edges of the different series of bars g as they turn around the drums.

Over the front of the grate and in front of the arch through which air is fed to the fire-chamber a feed funnel or hopper, I, is located, through which the slack, either alone or mixed with other fuel, is fed onto the front end of the grate. The grate is actuated by a sprocket chain or band leading from a pulley, K, driven by a suitable power to a corresponding pulley, k, fixed on the shaft of one of the drums F. Thus as the slack is fed onto the grate it will be carried thereby rearwardly, and before reaching the end of the grate will have been completely consumed, and the ashes will be carried by the grate over the rear drum F and dumped into the rear end of the ash-pit against the inclined wall D.

In order to remove the ashes as they fall, and thereby keep a free circulation of air beneath the grate, we provide the ash-remover, constructed as follows: Between the two front and two rear standards, e', sprocket-wheels L are mounted, and sprocket-chains l connect the sprocket-wheels at the front with the corresponding sprocket-wheels at the rear. To the said sprocket-chains l scoops M are secured, which, as they are carried by the chains rearwardly and upwardly in proximity to the inclined wall D, catch the ashes as they fall from the grate and conduct them toward the front and dump them into a pit prepared to receive them. In order to give the sprocket-chains l, with their scoops, the proper movement, an intermediate gear-wheel or sprocket-wheel—preferably a gear-wheel, N—is interposed between a sprocket-wheel, O, fixed to the shaft of the drum F, and a gear-wheel, o, fixed on the shaft of the sprocket-wheel L. A sprocket-chain, P, connects the sprocket-wheel O with a corresponding sprocket-wheel,

p, fixed to rotate with intermediate gear-wheel, N.

The grate, with its ash-moving mechanism and its feed funnel or hopper, is free to be rolled into and out of the furnace on the tracks a'. To prevent the slack or other fuel from falling down at the sides of the grate, guard-pieces Q are secured along the upper corners of the furnace.

Having thus fully described our invention, what we claim as new, and desire to secure by Letters Patent, is—

1. The combination, with a suitably-mounted endless carrier-grate, of an endless carrier ash-remover mounted beneath said grate and provided with scoops, substantially as set forth.

2. The combination, with a grate-supporting frame and the endless carrier-grate mounted in the frame, of an endless carrier ash-remover supported in the frame beneath the grate, substantially as set forth.

3. The combination, with the grate-supporting frame and the inclined ash-pit wall at the rear of the grate, of the endless carrier-grate supported in the frame, and the ash-remover consisting of a series of traveling scoops arranged to travel in proximity to the said inclined wall below the grate, substantially as set forth.

4. The combination, with the grate-supporting frame, the endless grate supported therein, and means for actuating the endless grate, of an ash-remover supported by the frame, and a connection between the ash-remover and the grate, whereby the motion of the grate imparts motion to the ash-remover, substantially as set forth.

In testimony whereof we have affixed our signatures in presence of two witnesses.

THOMAS WILKINSON.
JOHN GLENDINNING.
